UNITED STATES PATENT OFFICE.

BENJAMIN E. D. STAFFORD AND FREDERICK K. LANDGRAF, OF PITTSBURGH, PENNSYLVANIA, ASSIGNEES TO FLANNERY BOLT COMPANY, OF PITTSBURGH, PENNSYLVANIA.

STAY-BOLT STRUCTURE.

Application filed August 21, 1919. Serial No. 318,942.

To all whom it may concern:

Be it known that we, BENJAMIN E. D. STAFFORD and FREDERICK K. LANDGRAF, citizens of the United States, and residents of 5 Pittsburgh, in the county of Allegheny and State of Pennsylvania, have invented certain new and useful Improvements in Stay-bolt Structures; and we do hereby declare the following to be a full, clear, and exact description of the invention, such as will enable others skilled in the art to which it appertains to make and use the same.

This invention relates to improvements in staybolt structures for boilers,—one object of the invention being to provide a mounting for the headed outer end of a stay-bolt which shall be approximately flush at its outer end with the outer face of the boiler sheet; which shall effectually resist inward 20 pull of the staybolt; which may be quickly applied, and which will effectually enclose the bolt head and its bearing.

With this and other objects in view, the invention consists in certain novel features 25 of construction and combinations of parts as hereinafter set forth and pointed out in the claims.

In the accompanying drawings, Figure 1 is a sectional view showing an embodiment 30 of our invention, and Figures 2, 3 and 4 are views illustrating modifications.

1 represents an outer boiler sheet having an opening 2 in which the outer end portion of a sleeve or bearing member 3 is mounted.

35 The sleeve or bearing member may be made slightly conical and is formed internally, near its inner end, with a curved seat 4 for the rounded head 5 of a staybolt 6, and the inner end of the opening in the 40 sleeve or bearing member is made flaring to accommodate the "swing" of the staybolt.

The outer end of the sleeve or bearing member 3 is made with a flaring portion 7 which forms an inclined shoulder 8 which 45 rests against an inclined or flaring wall 9 of the opening 2 in the boiler sheet and the major portion of said sleeve or bearing member projects inwardly beyond the boiler sheet. By mounting the sleeve or bearing member 3 in the boiler sheet as above described, it will effectually resist or withstand inward "pull" of the staybolt. The outer end of the wall of the sleeve or bearing member is formed with two beveled faces 10 and 11 and the beveled face 10

forms, with a portion of the inclined or flaring wall 9 of the opening 2, a groove in which a weld 12 is located, said weld integrally uniting the sleeve or bearing member to the boiler sheet.

The interior of the sleeve or bearing member is formed (near its outer end) with an annular recess 13 forming a shoulder 14. A closure 15, which may be made in the form of a concave convex disk or plate, is 65 disposed at its peripheral portion in the annular recess 13 and is seated on the shoulder 14. The dimensions of the sleeve or bearing member and the form of the closure are such that a clearance 16 is formed for the bolt 70 head.

The closure 15 is sealed within the sleeve or bearing member and integrally united thereto by a weld 17 between the beveled face 11 of the latter and the outer face of the 75 closure.

It will be seen that the sleeve or bearing member is secured within the opening of the boiler sheet by welding and that said sleeve or bushing is closed and sealed by a closure 80 made rigid within the same by welding. The bolt head being permanently sealed within the sleeve or bearing member, the bolt should be provided with a tell-tale hole accessible from the inner end of the bolt. Thus, the 85 bolt may be provided with a tell-tale hole 18 extending from the inner end and terminating at its outer end within the headed end of the bolt.

In the construction shown in Figure 2, 90 a removable closure 19 is employed and made in the form of a threaded plug, the interior of the sleeve or bearing member being threaded as at 20 to receive the same. A gasket 21 may be disposed between the 95 plug or closure 19 and a shoulder 22 formed in the sleeve or bearing member. The outer end of the sleeve is formed with an annular enlargement 23, which provides the beveled faces 9 and 10.

In the construction shown in Figure 3, a bearing sleeve or member 24 is employed having its lower or inner portion curved as at 25 and the upper or outer end portion of the sleeve is mounted in the opening in the 105 boiler and welded to the latter and a removable plug or closure is employed, as previously explained in connection with the construction shown in Figure 2. The portion 26 of the sleeve shown in Figure 3 is approx- 110

imately cylindrical and hence the portion of the opening 2 in the boiler sheet through which it passes is also approximately cylindrical.

5 In the constructions shown in Figures 2 and 3, the removable closure is provided with an angular enlargement 27 to receive a wrench and the threaded portion in the sleeve to receive said closure may terminate 10 inwardly from the outer end of the sleeve.

In Figure 4, a tapering sleeve or bearing member 28 is employed and it is threaded interiorly at its outer end, as at 29 to receive a closure 30, the outer end of which 15 is approximately flush with the end of the sleeve and it is made with an angular recess 31 to receive a wrench.

When the construction shown in Figures 2, 3 and 4 are employed, in which removable closures are used, the bolt may be made 20 solid,—viz: without a tell-tale hole.

Having fully described our invention, what we claim as new and desire to secure by Letters-Patent, is:—

25 1. The combination with a boiler sheet provided with an opening having a flaring wall portion, of a bearing member provided at its outer end with an annular enlargement disposed intermediate the surface of

the sheet, said enlargement having two beveled portions, one of which is seated on the beveled wall portion of the opening in the boiler sheet, a weld between the other beveled portion of said enlargement and the beveled wall portion of the opening in the 30 boiler sheet, a bolt head mounted in said bearing member, and a closure in the bearing member over the bolt head.

2. In a staybolt structure, the combination with a boiler sheet provided with an 40 opening having a flaring wall, of a bearing member having an inclined shoulder near one end seated on said flaring wall, the end of said bearing member having two oppositely beveled faces, a staybolt having 45 a head mounted in said bearing member, a closure seated within said bearing member, a weld between one of said beveled faces of the bearing member and the flaring wall of the opening in the boiler sheet, and a 50 weld between the other of said beveled faces and the closure.

In testimony whereof we have signed this specification in the presence of a witness.

BENJAMIN E. D. STAFFORD.
FREDERICK K. LANDGRAF.

Witness:

EDWIN S. RYCE.
